UNITED STATES PATENT OFFICE.

JOHN REPETTO, OF PHILADELPHIA, PENNSYLVANIA.

METALLIC CRATE OR CASE FOR BOTTLES, JARS, AND THE LIKE.

No. 873,085.

Specification of Letters Patent.

Patented Dec. 10, 1907.

Application filed August 1, 1905. Serial No. 272,166.

To all whom it may concern:

Be it known that I, JOHN REPETTO, a citizen of the United States, and a resident of Philadelphia, State of Pennsylvania, have 5 invented certain new and useful Improvements in Metallic Crates or Cases for Bottles, Jars, and the Like, of which the following is a full, clear, and complete disclosure.

My invention relates to cases or crates for 10 bottles, etc., especially designed for use in transporting the same, and the object of the present invention is the production of a crate, or case, which is light in weight, strong and durable, and sanitary, the construction being 15 such that the crate cannot collect dirt and impurities, and such that every part is readily accessible for the purpose of washing or cleansing the same. Moreover, I have provided a construction, whereby the crate 20 can be easily and certainly identified, and one in which the identification marks cannot readily be removed or destroyed. I attain these objects by making my crate, or case, entirely of metal and open on all sides and 25 bottom, producing as it were, a skeleton crate, the various parts of which are braced, bolted and riveted together in a way to combine rigidity with lightness. Moreover, I secure in a permanent manner to both the 30 sides and ends, and in a manner to strengthen the crate, plates of sheet metal in certain of which the handles for lifting the crate are formed, and upon others of which suitable identification marks may be displayed.

35 Broadly, my invention consists in a skeleton metallic crate, the parts of which are assembled and secured together with a view to lightness, durability, cleanliness and certainty of identification.

40 For a full clear, and exact description of my invention, reference may be had to the following specification, and to the accompanying drawings, in which

Figure 1 is a perspective view of my crate, 45 the sheet metal on one side being broken away to permit a disclosure of the inner construction of the crate; Fig. 2, is a sectional view on the line 2—2 of Fig. 3, showing in addition to Fig. 1, one method of placing 50 marks of identification upon said crate; Fig. 3, is a sectional view on the line 3—3 of Fig. 2; Fig. 4, is a showing of the way in which the cross stays are secured to each other and to the sides and ends of the crate; Fig. 5 is a sectional view taken on the line 5—5, Fig. 1; Fig. 6, is a sectional view, on the line 6—6,

(Fig. 3), of a detail of construction; Figs. 7 and 8 are sectional views of a modification of my construction.

In my crate or case, I employ two integral 60 end pieces made of angle iron, each composed of two uprights 10, and connecting base piece 11. The tops of the uprights of said end pieces are secured together by a channel iron 12, mitered at its ends, as shown 65 in Fig. 1. Between the channel iron 12 and the top of said uprights is secured a piece of sheet metal 13, preferably triangular in shape, and fitted between the ends of the uprights 10 and on the front side of the said 70 piece of sheet metal is a rod 14, curved, or rounded, as at 14' on its face. Bolts or rivets 15, secure the channel iron and sheet metal to the upper ends of the uprights 10, while the rivets 16 secure the channel iron 12, 75 sheet metal 13, and bar 14 together to form the top of the end piece of the crate. Also secured between the uprights 10 by bolts or rivets 19, 20, are two parallel flat rods 17, 18, as plainly shown in Figs. 1 and 5. To the 80 upper rod or bar 17, the lower end of the triangular sheet metal piece 13 is secured by a rivet 21. Within the said triangular piece is an opening 22, adapted to form a handle, by having secured to the edges thereof and on 85 either side of said triangular sheet, edges 23, formed somewhat after the manner of a split ring having its outer sides rounded. The two halves of said ring are secured around the opening 22 in said plate by rivets 90 24 and form an edge to said opening to permit the crate to be lifted without injury to the hands.

The ends of the crate as above described, 95 are secured together at the tops by channel irons 25, mitered at their ends, and abutting the channel irons 12 of the ends of the crate; and near the bottom by two flat bars or rods 26 and 27, similar to the rods 17 and 18. Between the channel iron 25 and the ends 100 10, is secured a strip of sheet metal 28 to the outside and top of which, and between the ends of the uprights 10, the bead 29, with a rounding or curved face 29' similar to the rod or bar 14, is secured by rivets 16'. The 105 channel iron 25 and the metal strip 28 are fastened to the ends 10 of the end pieces by rivets or bolts 30, while the bars 26, 27 are secured to the uprights 10 by rivets 31, 32 as clearly indicated in Fig. 5.

Extending between the rods 26—26 and 110 17—17, and also between the rods 27, 27,

and 18, 18 are cross stays 33, the construction of which is shown in detail in Fig. 4. Each stay is notched at suitable intervals corresponding approximately to the diameters of 5 the bottles to be crated, as shown at 34, said notches extending half way of the width thereof, and each end of each cross stay is provided with an integral stud or rivet 35 adapted to be passed through apertures in 10 the rods 17, 18, 26 or 27 and to be headed over or riveted to said rods as clearly indicated in Fig. 3. Thus it will be seen that the cross stays 33 form a series of pockets in which the bottles or jars are preserved in an 15 upright position and being permanently made fast to the side and ends add great strength and rigidity to the whole crate. Extending between the bases 11 on the end pieces, and located midway of the pockets or 20 cells formed by the intersection of the rods or cross stays 33, are bottom bars 36 riveted to the base angle iron 11 by rivets 37, and adapted to form a support for the bottles or jars when the crate is lifted.

25 The strips 28 are adapted to receive identification marks, either of the ownership of the crate, or the character of goods handled in the crate, which marks may be made thereon either by enameling the same, on the 30 outer sides of said narrow strip or by perforating or punching the characters through the sheet metal, as shown in Fig. 2.

35 By means of the above features of construction, and arrangement, I have produced a light strong crate in which there is very little surface to catch or retain dirt or dust, and, moreover, one in which every part can be cleaned and washed with utmost facility. I have also produced a vessel suitable for 40 packing and storing, made up of sheet metal and structural bars, the upper portion of which is not only inclosed but also strengthened by the utilization of sheet metal, the upper edges of which material are bound between the structural bars in such a manner as 45 to cause the upper edge of the crate to possess great strength and durability, and to stiffen the structure in general. The lower portion of the crate is skeleton, and by virtue of being 50 made up of structural bars in the manner hereinbefore described possesses lightness, durability and simplicity of construction. By the embodying of a strip of sheet metal in the construction of the crate, and at the 55 same time having the said strip in such a position that it may be adapted to receive marks of identification is another entirely new feature in frame structures, which enables skeleton crates to be identified without 60 any additional signs or other marks being attached thereto.

In Figs. 7 and 8, I have illustrated a modification in which I have added to the construction above described, additional angle 65 irons 38, running lengthwise of the crate se-

cured by suitable bolts or rivets 39 to the corners formed by the uprights 10 and base piece 11. This angle iron 38, besides imparting additional stiffness to the crate, prevents bottles from being lifted from the bottom rods 36 when the crates are set on an uneven surface, projections on which would extend above the plane of the bottom of the bottles. It enables one to set the crate in almost any place without disturbing the positions of the bottles or forcing them upward from their seats.

Having thus described my invention, what I claim and desire to protect by Letters Patent of the United States, is:—

1. A metallic crate comprising end angle irons bent to form a U-shaped frame, having its free ends connected by channel irons, a sheet metal plate substantially triangular in shape and bound at its corner portions and along one side of its base to web portions of the crate bars, the said plate having an opening therein to act as a handle.

2. In an all metallic crate for bottles etc., the combination of end angle irons bent to form two parallel uprights and a base piece, channel bars secured to the tops of said uprights, sheet metal plates secured between said channel irons and the tops of the said uprights, the sheet metal plates at the ends being provided with handles, parallel rods connecting the lower ends of said uprights and cross stays forming pockets or cells secured to said parallel rods.

3. In an all metallic crate for bottles, etc., the combination of end angle irons bent to form two parallel uprights and a base piece, parallel rods connecting the lower end of said uprights, channel irons secured to the tops of said uprights, sheet metal plates secured between the said channel irons and the tops of said uprights, the plates at the ends of said crate being triangular in shape, and secured to one of said parallel rods and provided with handles, cross stays forming pockets or cells secured to the said parallel rods and bottom bars for supporting the bottles.

4. In a skeleton case for bottles, the combination of end pieces composed of integral angle irons bent to form a base piece and uprights extending at right angles to said base piece, a channel iron connecting the top of said arms of each end piece, sheet metal plates substantially triangular in shape secured between said channel irons and the ends of said uprights and a rod or bar curved on its outer face also extending between the ends of the said uprights and located on the outside of said triangular sheet, and parallel cross bars, provided with holes, near the bottom of said integral angle irons, to the top one of which one corner of each triangular plate is secured; of sides composed of channel irons connecting the tops of the two end

pieces, strips of sheet metal secured between the tops of said end pieces and said channel irons, curved faced rods or bars secured to the outside of said sheet metal, and parallel bars provided with rivet holes securing the bottoms of said end pieces together; cross stays arranged at right angles to each other, at suitable intervals apart, notched to secure the same to each other and provided with integral lugs or extensions to pass through the holes in said parallel bars and to be headed over or riveted to said bars; and bottom rods extending between said end pieces providing means for supporting the bottles between said cross stays.

5. In an all metallic crate for bottles, etc., the combination of end pieces made of angle iron bent to form a base and parallel uprights, a top composed of channel iron extending between said uprights, rods having a curved outer face arranged parallel to said channel irons and adjacent thereto, and sheet metal strips secured between said channel irons and said curved faced rods.

25 6. In an all metallic crate, comprising end angle irons bent to form a U-shaped frame, a bar connecting the free ends of said frame and a plate having an edge portion also connecting the free ends of the said frame and secured between said bar and said frame, the frame, plate and bar all being fastened together.

7. An all metallic crate comprising end angle irons bent to form a U-shaped frame, a bar connecting the free ends of said frame, a plate having an edge portion also connecting the free ends of said frame in front of said bar, the frame, plate and bar being fastened together, and another bar having its ends secured to said U-shaped frame in parallel relation to the first mentioned bar and secured to a portion of said plate.

8. In an all metallic crate comprising end angle irons bent to form a U-shaped frame, channel bars connecting the free ends of said frame, a plate substantially triangular in shape having an edge portion also connecting the free ends of said frame in front of said bar, the frame, plate and bar being fastened together, and another bar having its ends secured to said U-shaped frame in parallel relation to the first mentioned bar and secured to the apex of said triangular plate.

55 9. An all metallic crate comprising end angle irons bent to form a U-shaped frame, a bar connecting the free ends of said frame, a plate having an opening therein and having an edge portion secured to the front of said bar, and another bar having its ends secured to said U-shaped frame in parallel relation to the first mentioned bar and secured to a portion of said plate.

10. An all metallic crate comprising end angle irons bent to form a U-shaped frame,

a bar connecting the free ends of said frame, a plate having an opening therein and having an edge portion secured to the front of said bar, another bar having its ends secured to said U-shaped frame in parallel relation to the first mentioned bar and secured to a portion of said plate, and a bead located between the extremities of said frame, the said bead, plate and first mentioned bar being fastened together. 75

11. A metallic crate comprising end angle irons bent to form a U-shaped frame, the free ends of each frame being connected by end bars and side bars, side plates and end plates fastened respectively to the web portions of said free ends between the same and the respective end and side bars, the said plates having one or more free edges. 80

12. A metallic crate having its end frames formed of angle bars, a sheet metal plate substantially triangular in shape, bound at its corner portions and along one side of its base to separate parts of the frame bars, the said plate having an opening therein and a split ring binding the edge of said opening. 90

13. In a metallic crate having its side frames formed of angle bars, a sheet metal plate adapted to receive means of identification, the said plate having its bottom edge free and its top and side edges secured to the top and side webs of said angle bars. 95

14. A metallic crate comprising end angle bars bent to form a U-shaped frame, sheet metal plates connecting the end webs and side webs of the free ends of said angle bars, the said plates having one or more free edges, and channel bars also connecting the end and side webs of the free ends of said angle bars, the said webs, plates and channel bars being fastened together with each of the plates between the said frame and one of the said channel bars. 100

15. A metallic crate comprising end angle bars bent to form a U-shaped frame, sheet metal plates connecting the end webs and side webs of the free ends of said angle bars, channel bars also connecting the end and side webs of the free ends of said angle bars, the said webs, plates and channel bars being fastened together, and beads located between the webs of said angle bars and secured to the said plates and channel bars. 115

16. In an all metallic skeleton crate, the combination with a pair of end frames and side bars connecting together said end frames, of an identification strip secured between said end frames and said side bars and extending the length of said crate and a bead extending between said end frames and binding the top edge of said protective strip to said side bars. 120

17. In an all metallic skeleton crate, the combination with a pair of end frames, the top bars connecting the upper ends of said end frames, pairs of bars adjacent and par- 125

allel to the bottom of said crate extending across said end frame and connecting said end frames together and intermeshing cross stays, forming pockets, having their ends secured to said paralleled bars.

18. A metallic crate, comprising a skeleton frame having its vertical bottom and top edges formed out of structural bars, sides and bottom slats secured to the webs of said bars, 10 and sheet metal plates fastened to the webs and slats around the upper portion of the crate.

19. A metallic crate, comprising a skeleton frame having its vertical and lower edges 15 formed of angle bars and its top edges formed of channel bars, sides and bottom slats secured to the webs of the angle bars, and sheet metal plates fastened to the webs and slats around the upper portion of the sides.

20. A metallic casing having its edges

made up of structural bars, and the lower portions of its sides, ends and bottom made up of slats crossing each other, and fastened at their extremities to the webs of said bars.

21. A metallic casing having its edges 25 made up of structural bars, and the lower portions of its sides, ends and bottom made up of slats crossing each other, and fastened at their extremities to the webs of said bars, the upper portions of said sides and ends being formed of sheet metal plates, having their upper edges secured to the top edge of 30 the crate and their lower edges secured to the top slats.

In witness whereof, I have hereunto set 35 my hand this 12th day of July, A. D., 1905.

JOHN REPETTO.
